UNITED STATES PATENT OFFICE.

EARL H. ISRAEL, OF ST. LOUIS, MISSOURI.

WATER-CLOSET.

SPECIFICATION forming part of Letters Patent No. 434,340, dated August 12, 1890.

Application filed March 29, 1890. Serial No. 345,821. (No model.)

To all whom it may concern:

Be it known that I, EARL H. ISRAEL, of the city of St. Louis, in the State of Missouri, have invented a certain new and useful Improvement in Water-Closets, of which the following is a full, clear, and exact description, reference being had to the accompanying drawings, forming part of this specification.

10 My invention relates to certain improvements in water-closets; and my invention consists in features of novelty hereinafter fully described, and pointed out in the claims.

Figure I is a side elevation illustrative of my invention, the cistern or tank being shown in section. Fig. II is a top or plan view, the tank not being shown. Fig. III is a horizontal section taken on line III III, Fig. I. Fig. IV is a vertical section showing the condition 20 of the parts just after the siphon is formed and the flush of the bowl (not shown) commenced. Fig. V is a similar view showing the condition of affairs after the flushing is completed, the siphon broken, and the refilling of the tank commenced. Fig. VI represents a modification of my preferred form of invention.

Referring to the drawings, 1 represents a suitable tank or cistern, and 2 part of the 30 pipe leading therefrom to the bowl of the closet.

3 represents the long leg, and 4 the short leg, of an ordinary siphon arranged within the tank, and the long leg of which communicates with the bowl-pipe 2.

5 represents an ordinary valve operated by a lever 6, chain 7, and rod 8, as usual, to open communication between the tank and the long leg of the siphon when the bowl is 40 to be flushed.

9 represents the supply-pipe of the tank, 10 the valve of the pipe, and 11 the float of the valve.

I claim no invention in any of the parts, 45 *per se*, thus far mentioned, as they may be of any of the desired forms and constructions now well known in the trade.

13 represents a chamber located in the bottom of the tank or cistern 1, and which has 50 an upwardly-extending air-tube 14, preferably held to the top of the chamber by a neck

15 on the top of the latter, and a set-screw 16, passing through the neck and jamming against the tube. The tube is thus adjusted in height. Within the chamber 13 is a second chamber 17, open at top. 55

18 represents a pipe leading from the chamber 17 up through the tube 14 and communicating with the upper portion of the siphon. (See Figs. IV and V.) A space or passage- 60 way is left between the pipe 18 and tube 14.

19 represents a short tube or pipe extending from the lower portion of the chamber 13 into the short leg 4 of the siphon.

The operation is as follows: The valve 5 65 being opened, the siphonic action is formed and the water starts to flow from the tank up the short leg of the siphon down the long leg of the siphon into the pipe 2 leading to the bowl. (See arrows, Fig. IV.) The 70 valve 5, being released as soon as the siphon is formed, closes. While the water is passing from the tank through the siphon, it is also being exhausted from the chamber 13 through the pipe 19 and the siphon, and is 75 also being exhausted from the chamber 17 through the pipe 18 and the siphon, as shown by the arrows in Fig. IV. The siphon will remain unbroken and the water continue to run from the tank into the bowl until the water in the chamber 17 is reduced to the lower 80 open end of the pipe 18, and then the air which has passed down the tube 14 into the chambers 13 and 17, as the water was removed, passes up the pipe 18 and breaks the 85 siphon. The duration of flush may be regulated by adjusting the tube 14 up or down, for it is evident that the lower the top of the tube is beneath the surface of the water before the siphon is started the longer the duration of 90 the flush will be, for the height of this tube regulates the period of time it takes to empty the chambers 13 and 17, which are filled through this tube when its upper end is beneath the surface of the water. As soon as 95 the siphon is broken the water in the short leg of the siphon seeks the level of the water in the tank, (see Fig. V,) the chambers 13 and 17 being immediately refilled by water passing through the pipe 19, so that the siphon 100 may again be started.

It will be observed that the chambers 13

and 17 will be filled through the pipe 19, whether or not this pipe extends into the short leg of the siphon, and the pipe could be located outside the short leg of the siphon, 5 (the pipe 18 alone being utilized to drain the chamber when the siphon is working,) but I prefer to place the pipe 19 within the short leg of the siphon, as shown, so that the water in the chamber 13 will be drained (when the 10 siphon is working) beneath the top of the chamber 17, so that when the siphon is broken, as described, there will be a short lapse of time before the water entering through the pipe 19 will flow into the chamber 17, (it 15 having first to fill the space between the chambers,) so that there is no liability of the siphon starting again before enough air enters through the pipe 18 to break it. By an arrangement of this kind a most effective 20 and durable device is produced wherein no valves are employed to get out of order and a uniform action can be implicitly relied upon. The construction, moreover, is comparatively cheap and uncostly.

25 In Fig. VI, I have shown a modification wherein the chamber 17 and the pipe 18 are omitted and the tube 14 is made shorter than in my preferred form, while the pipe 19 is made longer than in my preferred form. In 30 this form of my invention the water enters the chamber 13 through the tube 14, which may be adjusted up or down to make a long or short wash, as desired. When the siphon is started, and after it has reduced the water in the cistern to the level of the upper 35 end of the tube 14, the water is exhausted from the chamber 13 by the pipe 19, air entering the chamber through the tube 14 as the water is exhausted. When the water is exhausted from the chamber, the air enters 40 through the pipe 19 into and breaks the siphon. Then, as the cistern is refilled through the valve 10, the chamber 13 is refilled through the tube 14. This form of my invention may 45 be used where but a single wash is wanted at a time and a wash of a practically fixed duration.

In washout and siphon closets it is desirable to retain in the bowl after each flush a 50 body of water. I have devised a very cheap and effective means for maintaining a supply of water in the bowl, and it consists of a cylinder or cylinders 20, arranged within the tank or cistern and provided with an open-ended 55 pipe 21 extending from its bottom to near its top. The tube communicates at bottom with the long leg of the siphon through means of a small pipe 22 and at top through means of a larger pipe 23. Now when the siphon is started 60 the action of the water flowing through the siphon produces a partial vacuum in the cylinder 20 and the water immediately flows through the pipe 21 and fills the cylinder. The pipe 23 being much larger than the pipe 65 22, the water enters the cylinder much faster than it can escape, the result being that after the siphon is broken there is a supply of water

in the tube, which, escaping through the pipe 22, passes to and fills the trap and partially fills the bowl after the flush is completed. This 70 part of my invention also operates without the use of valves, and is entirely automatic and reliable.

I claim as my invention—

1. The combination of a water tank or cistern, a siphon communicating with the bowl-pipe, a chamber provided with an air-tube, and a pipe extending from the chamber to the upper part of the siphon, substantially as set forth. 75

2. The combination of a water tank or cistern, a siphon communicating with the bowl-pipe, a chamber provided with an air-tube, a pipe extending from the chamber to the upper part of the siphon, and a pipe extending from 85 the chamber to the lower part of the siphon, substantially as set forth.

3. The combination of a water tank or cistern, a siphon communicating with the bowl-pipe, a chamber provided with an adjustable 90 air-tube, a pipe extending from the chamber to the upper part of the siphon, and a pipe extending from the chamber to the lower part of the siphon, substantially as set forth.

4. The combination of a water tank or cistern, a siphon communicating with the bowl-pipe, an outer and an inner chamber located at the bottom of the tank or cistern, an air-tube communicating with said chambers, a pipe extending from the inner chamber to the 100 upper part of the siphon, and means for refilling the chambers with water, substantially as set forth. 95

5. In a siphon-closet, the combination, with the tank and siphon, of a cylinder closed at both ends and having upper and lower communication with the siphon, and a pipe open at both ends communicating at its upper end with the upper part of said cylinder and at its lower end directly with the tank, substantially as set forth. 105

6. The combination of a water tank or cistern, a siphon, an outer and an inner chamber, upper and lower communications between the siphon and the chambers, and an air-supply to the chambers, substantially as and for the purpose set forth. 115

7. The combination of a water tank or cistern, a siphon, a chamber located in the lower part of said tank or cistern and having communication with said siphon, and an adjustable air-supply pipe connected to said chamber, substantially as and for the purpose set forth. 120

8. The combination of a water tank or cistern, a siphon communicating with the bowl-pipe, an outer and an inner chamber located at the bottom of the tank, an adjustable air-tube, a pipe extending from the lower part of the inner chamber to the upper part of the 130 siphon, and a pipe extending from the lower part of the outer chamber into the short leg of the siphon, substantially as and for the purpose specified. 125

9. The combination of a water tank or cistern, a siphon communicating with the bowl-pipe, a tube located within the tank, an open-ended pipe located within the tube, a small pipe forming a communication between the lower part of the tube and the siphon, and a larger pipe forming a communication between the tube and the upper part of the siphon, substantially as and for the purpose set forth.
10. In a water-closet, the combination, with the siphon, of a cylinder having upper and lower communication with the siphon, and a pipe open at both ends within the tube, substantially as and for the purpose set forth.
11. In a water-closet, the combination, with the tank and the siphon, of a cylinder independent of said siphon, closed at both ends and having upper and lower communication with the said siphon, and a pipe open at both ends communicating at its upper end with the upper part of said cylinder and at its lower end directly with the tank, substantially as set forth.

EARL H. ISRAEL.

In presence of—

E. S. KNIGHT,
THOMAS KNIGHT.
